[57] CLAIM

The ornamental design for a window mounted electric
candle or similar article, substantially as shown and
described.

DESCRIPTION

FIG. 1 is a front elevational view of a window mounted
electric candle or similar article showing my new de-
sign;

FIG. 2 is a rear elevational view thereof;

FIG. 3 is a right side elevational view thereof, the left
side being a mirror image;

FIG. 4 is a top plan view thereof;

FIG. 5 is a bottom plan view thereof;

FIG. 6 is a top perspective view thereof on a reduced
scale, the window frame, electric bulb, and electric cord
being shown in broken lines for illustrative purposes
only.
